United States Patent Office

Des. 202,932
Patented Nov. 16, 1965

202,932

JUG

Richard L. Platte, Ann Arbor, Mich., assignor to Hoover
Ball and Bearing Company, Saline, Mich.

Filed Apr. 29, 1965, Ser. No. 85,027

Term of patent 14 years

(Cl. D58—5)

FIG. 1

FIG. 2

FIG. 3

FIG. 4

FIGURE 1 is a side elevational view of a jug showing my new design;

FIGURE 2 is a rear elevational view thereof;

FIGURE 3 is a front elevational view thereof; and

FIGURE 4 is a top plan view thereof.

The dominant features of my new design reside in the portions shown in full lines.

I claim:

The ornamental design for a jug, substantially as shown and described.
